UNITED STATES PATENT OFFICE.

HARRY THOMAS, OF OAKDALE, TENNESSEE.

AUTOMATIC LOCKING AND RELEASING MEANS FOR SWITCH THROWS.

Application filed July 14, 1926. Serial No. 122,461.

The object of this invention is to provide a switch throwing device including a lever and switch handle, with locking means automatically engaged when the lever is fully thrown, and released upon the initial movement of the handle when the position of the switch is to be changed.

A further object is to provide a simple construction which cannot, except under the most extreme conditions get out of working order, and a device in which only a single movement of the switch handle is required for producing the entire operation, even when the switch has been locked under strain due to the sticking of the switch point, or other causes.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a view of the construction in side elevation.

Figure 2 is a perspective view of the main portion of one of the switch stands.

Figure 3 is a vertical section thru one of the switch stands, with a pivoted trigger mounted therein.

Figure 4 is a perspective view of the lever to be connected directly with the switch mechanism.

Figure 5 is a perspective view of the switch handle, the offset end of which passes thru the block of Figure 6, and thru the forked portions of the lever of Figure 4.

Figure 6 is a perspective view of the block to be mounted in the fork of Figure 4, the block being proportioned for effecting locking connection with either of the triggers shown in Figures 7 and 8.

Figures 7 and 8 are perspective views of the triggers to be mounted respectively in the switch stand, one of which is shown in Figure 2, and the other of which appears in Figure 3, the latter having the lower edge of the opening beveled reversely, with reference to the device of Figure 2.

The switch stands 10 and 11 are carried by base 12, and the switch operating lever 13 connects with rod 14, and is movable angularly with reference to mounting element 15.

The switch stands are each provided with an opening such as 16, and the lower edge portions of these openings, are beveled as shown at 17 and 17', the bevels being in reverse relation. The triggers of Figures 7 and 8 are mounted in the switch stands 10 and 11, being pivoted by means of rods or bolts 18, and the triggers are each provided with shoulders as is indicated at 19 for contact with an adjacent surface, that is with the outer surface of the switch stand or stands, so that movement of the triggers under gravity is limited, and the locking elements carried thereby are properly positioned by the automatic return of said locking elements to normal position. The triggers or locking elements, designated 21 and 22 are provided with projecting lugs, the double trigger 21 including two lugs 23, and the trigger 22 including one lug 24 in the central portion of one face,—the lugs 23 of element 21 being spaced as illustrated in Figure 7.

The switch lever 13 to be connected directly with the switch mechanism includes a head 25, and prongs 26, the complete device at the end of element 13 constituting a fork, and the portions 26 being cut away at 26' to fit over the shoulders 27 of the switch stands. The prongs 26 are apertured transversely as indicated at 28, and the offset end of switch handle 30 passes thru apertures 28 and thru the block 31 of Figure 6.

The offset end of handle 30, is square in cross section at the point 33, and this portion fits the square bore 34 of Figure 6, the block 31 being mounted between the prongs 26, and having limited movement with reference to switch lever 13, as indicated in full line and dotted line position in Figure 1. This movement is limited when edge 31' engages the head 25, upon movement in one direction, or when bevel surface 31'' engages the head 25, upon movement in the other direction, the play permitted, determines the position of the block 31 with reference to the trigger, it being observed in Figure 1 that when handle 30 is in full line position, the trigger at the right is engaged, and the switch lever 13 and the switch control thereby, but not shown, is securely retained in the desired position.

Upon lifting handle 30 to the dotted line position of Figure 1, the block 31 is released from the trigger which it has just engaged,

and this initial movement of the handle 30 is continued in the same direction, for the purpose of lifting and throwing switch arm 13 when the portion 31' of the block 31 comes into engagement with head 25.

The particular form of the block of Figure 6 is important, this block including the grooved portion 37, and the tongue or lug 38 of angular form and positioned intermediate of the portions 39 and 39' formed by the middle groove 37. The triggers of Figures 7 and 8 are formed respectively with lugs 23, spaced as shown, and with a central lug 24, so that the block of Figure 6 first engages and then throws out either trigger, so that the handle may pass to final position as shown in full lines in Figure 1. The central lug 38 now engages and is locked by the trigger 22 and especially the central lug 24 thereof. In the other position of the switch lever and handle, the spaced lugs 23 are engaged by the spaced portions 39 and 39' of block 31, so that the character of the locking arrangement is similar on opposite sides, that is in opposite positions of the switch handle, but the elements which produce the locking contact differ in the respect indicated, and because of the cooperation between the block of Figure 6, with the trigger of Figure 7 or with the trigger of Figure 8, as the case may be. When throwing the switch lever and handle, the prongs of the fork pass on opposite sides of the switch stands and act as guiding devices, and the side walls of the grooved portion of the block also act as guiding elements when passing the pivoted block engaging device carrying a central lug or tongue.

Having described the invention what is claimed is:—

1. In a device of the class described, a switch lever and a handle therefor movable angularly with reference to the lever, a block movable angularly by the handle, switch stands and pivoted block retaining devices mounted on the stands, the retaining devices including lugs adapted to project into the path of the block, and the lugs on oppositely located retaining devices being out of aline-

ment, for engagement with different portions of the block, preventing reverse movement of the lever prior to the release of the block by angular movement of the handle. 50

2. In a device of the class described, a switch lever and a handle therefor movable angularly with reference to the lever, a block movable angularly by the handle, one surface of said block being grooved toward one end, and the block including a tongue projecting from the surface thereof in approximate alinement with the groove for engagement respectively with the tongue and the grooved portions of the block preventing reverse movement of the lever prior to the release of the block by angular movement of the handle. 55 60 65

3. In a device of the class described, a switch lever and a handle therefor movable angularly with reference to the lever, a block movable angularly by the handle, means for limiting the movement of the block, switch stands and pivoted block retaining devices mounted on the stands, said devices being movable by gravity towards each other and including lugs movable into the path of the block after the lever is thrown by the handle, said handle moving the block upon the initial operation thereof out of the path of the pivoted retaining devices and thereafter throwing the lever by continued movement in the same direction, said block including projecting elements positioned to engage either retaining device to the exclusion of the other. 70 75 80

4. In a device of the class described, a switch lever and a handle therefor movable angularly with reference to the lever, a block movable angularly by the handle, switch stands and pivoted block retaining devices mounted on the stands, said block and block retaining devices including members causing the block to effect engagement at one end portion of the block with one of the retaining devices, and at the other end portion of the block with the other retaining device. 85 90 95

In testimony whereof I affix my signature.

HARRY THOMAS.
